UNITED STATES PATENT OFFICE.

LAWRENCE F. SMITH, OF HAZARD, KENTUCKY.

RERAILER.

Application filed April 28, 1923. Serial No. 635,323.

To all whom it may concern:

Be it known that I, LAWRENCE F. SMITH, a citizen of the United States, residing at Hazard, in the county of Perry and State of Kentucky, have invented a new and useful Rerailer, of which the following is a specification.

This invention relates to rerailers the primary object of the invention being to provide a device of this character which will facilitate the rerailing of derailed railway rolling stock.

Another object of the invention is to provide a rerailer which will securely grip a rail of a track to insure against lateral movement thereof, while a car is being moved thereover, the connection between the rail and rerailer being such as to permit the rerailer to be readily and easily positioned or removed from its position adjacent to a rail.

A still further object of the invention is to provide a device of this character having a relatively broad supporting surface to insure against rocking of the rerailer when a car moves thereover.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a plan view of the rails of a track disclosing a rerailer constructed in accordance with the invention as positioned for use.

Figure 2 is a side elevational view of the rerailer as applied to the rail of a track.

Figure 3 is a sectional view through a rail and that portion of the rerailer that secures the rerailer to the rail.

Figure 4 is a perspective view of the rerailer.

Referring to the drawing in detail, the rerailer includes a body portion indicated generally by the reference character 5, the upper and lower edges of the rerailer tapering towards the ends thereof as clearly shown by Figure 4 of the drawing, to pre-

sent inclined tracks over which the wheels 65 of a car move, on being rerailed.

As shown, a flange 6 is formed along one edge of the body and extends throughout the entire lengths thereof, the flange 6 at one end of the rerailer is relatively wide and narrows as it merges into the body portion 60 at the opposite end of the rerailer, while at the opposite end of the rerailer, and extending laterally from the opposed edge thereof, the flange 7 is relatively wide and merges 65 into the body portion adjacent to the end of the body portion where the opposed flange 6 is widest.

Formed on the under surface of each flange is a relatively thick portion indicated 70 at 8 which has its upper surface cut away at 9 to provide a clearance for the flange of a wheel, as the wheel passes over the upper edge of the rerailer thereof, onto a rail. Extending from these thickened portions 8 of the rerailer are hook members indicated at 10, which lie in such relation with the side faces of the body portion as to cooperate 75 with the adjacent side faces of the body portion to clamp a rail to insure against movement of the rerailer.

Thus it will be seen that due to this construction, the end of the rerailer fitted over a rail, is securely held against lateral movement. Openings 11 are formed in the rerailer at points adjacent to the widened ends of the flanges 6 and 7, which openings may accommodate spikes affording means to spike the rerailer to the ties of a track to insure against the rerailer moving laterally 80 at the tie engaging end thereof.

Used in conjunction with this rerailer, is a rerailer section 12 which is formed with an inclined upper surface, the upper end of the section 12 lying in a plane with the tread of the rail associated therewith, so that the wheel of a car may readily pass from the rerailer section 12 onto the rail.

Openings 13 are formed in this section 12 so that the section may be spiked to the ties 100 on which the same is supported. From the foregoing it will be obvious that while I have provided a rerailer, which is shown as secured on the outer sides of rails, it is to be understood that by reversing the rerailer and employing the opposed hook member 10, the rerailer may be positioned to lie between 105 the rails of a track section.

It might be further stated that openings 14 are formed in the body portion intermediate its ends, which openings receive suitable bracket members or hooks whereby the 5 device may be readily supported.

What is claimed as new is:—

1. A rerailer including a body portion, said body portion having its opposed edges tapering from the center to the ends thereof, flanges formed integral with the body portion and extending laterally from the edges thereof, each of said flanges including a relatively wide portion to provide supporting surfaces, each flange having an outer camming edge, and a hook member formed adjacent to each end of the body portion.
- 15 2. A rerailer including a body portion, said body portion being relatively wide at a

point intermediate its ends, said body portion tapering from the center to the ends thereof, integral laterally extending flanges formed along the edges of the body portion, each of the flanges having a relatively thick portion, the relatively thick portions being partially cut away to provide clearances for wheel flanges, hook members formed integral with the flanges, and said flanges having inclined opposed edges.

In testimony that I claim the foregoing as my own, I have hereto affixed my signature in the presence of witnesses.

LAWRENCE F. SMITH.
